FIXED RESILIENT CLIP TO HOLD ARTICLES

William N. Aleshin, South Windsor, Conn.

Application June 17, 1950, Serial No. 168,714

1 Claim. (Cl. 24—259)

1

This invention relates to clips and more particularly to clips which are adapted to be attached to a tobacco lath for detachably receiving individual tobacco stalks or bunches of tobacco leaves.

It is an object of my invention to provide a novel spring clip which will facilitate the attachment of tobacco stalks to the lath upon which a plurality of my improved clips are fastened, and also the handling of the lath with the said stalks attached thereto.

A further object is the provision of a spring clip which is expandable to receive stalks of tobacco plants, bunches of leaves or stems of individual leaves.

A further object of this invention is the provision of such a spring clip which may be used for supporting various articles, such as brooms and other tools, and which may be readily attached to or detached from a member upon which the said clip is mounted.

Further objects and advantages of this invention will be more clearly understood from the following description and from the accompanying drawings in which:

Fig. 1 is a plan view of a portion of a lath having a plurality of my improved clips fastened thereto, one of the clips being shown in central horizontal section and the other clips being shown supporting tobacco stalks of different sizes.

Fig. 2 is a front view of said lath portion showing tobacco stalks attached thereto; one of the clips being shown in central vertical section.

Fig. 3 is an end view thereof.

Fig. 4 is a front view of the lath showing the swivel operation of the clips thereon.

Fig. 5 is a plan view of the clip showing the same in position to be attached to or detached from the lath.

Fig. 6 is a plan view of a modified form of spring clip.

Fig. 7 is a front view of said modified form of clip.

Fig. 8 is a plan view illustrating a further modified form of spring clip.

Fig. 9 is a front view thereof.

As illustrated in the drawings, the numeral 5 denotes a tobacco lath of conventional form such as commonly constructed of wood or other suitable material.

The present invention provides a series of spring clips 6 which are spaced upon the lath and attached thereto preferably by means of a fastening member such as a nail 7 or the like.

2

Each spring clip is constructed of spring metal, preferably in sheet form, and comprises a loop 8 having a foot portion 9, a lead portion 10 and a finger 11 which extends into the loop 8.

The foot portion 9 has at the end thereof a raised projection 12 with a reversely extending free edge portion which is adapted to rest upon the surface of the lath 5 to facilitate the insertion of a tobacco leaf or stalk or stem into the loop 8. The said foot portion is also preferably formed with a notch 13 for receiving the shank of the nail 7 underneath the head thereof and the said notch opens into a slit 14 which forms an engaging tongue 15 for retaining the clip in engagement with the nail.

The lead portion 10 is preferably provided by an extension from the loop 8; the said portion extending outwardly and back over the loop to provide a guard which engages the tobacco stalk or stem and opens the loop 8 to permit entry of said stalk or stem into the loop.

The finger 11 is formed as an extension from the lead portion 10 and may be cut from a portion of the loop 8 leaving a slot 16 in said loop which will render more flexible the receiving portion of the loop. It will be noted that the said finger 11 is curved concavely so as to more adequately engage the surface of the stalk or stem and retain it in the positions clearly illustrated in Fig. 1.

As illustrated in Fig. 5, the said spring clips are attached to the lath by simply opening the clip to an extent wherein the tongue 15 will be raised above the head of the nail 7, which has previously been driven into the lath the required distance, so that the said clip may be slipped over the nail by permitting the said head to pass under the tongue. This provides for readily replacing clips when necessary.

As illustrated in Fig. 4, the said clips will swivel upon the nail 7 and thereby permit the tobacco leaves to hang vertically when the lath is turned towards a vertical position such as it assumes when being handed to a person who is hanging the lath or when the lath is hung by one end.

In the modified form illustrated in Figs. 6 and 7, the lead portion 10-a of the clip is doubled back upon itself to provide the spring finger 11-a. This form of clip eliminates the necessity of cutting the finger out of the material of the loop and, in addition, provides a retaining finger of greater strength than the finger in the form of clip illustrated in Fig. 1.

In the modified form illustrated in Figs. 8 and

9, the loop 8-b has a widened portion 17 from which a pair of lead portions 18-18 project forwardly. These lead portions are then bent rearwardly upon themselves and extend to the opposite side of the loop adjacent the sides thereof. It will be noted that, in this modified form, the foot portion extends forwardly for a greater distance than in the other forms and has a higher raised projection 12-b for more securely retaining the stalk or stem of the tobacco in position within the loop.

In the use of my improved lath, the stalks or stems of the tobacco are inserted into the loops of the spring clips by simply being moved against the lead portions of the clips with a rolling motion in a counterclockwise direction.

This motion will tend to raise the lead portion of the clip outwardly so as to open the clip and permit entrance of the stalk or stem into the loop wherein the spring tension in the loop will cause the finger portion 11 to be pressed into contact with the said stalks or stems and thereby securely retain the tobacco in position upon the lath.

When it is desired to strip the tobacco from the lath, it is simply necessary to remove it with a sweeping movement from left to right which movement will cause the individual pieces of tobacco to force the clips open and thereby permit passage of the tobacco out of the loops. In this manner, the tobacco may be quickly stripped from a lath by a single sweeping motion of the hand leaving all of the tobacco from the lath in a bunch in the hand of the operator.

I claim:

A spring clip constructed of a single strip of

resilient sheet metal and formed to provide a substantially circular loop having a receiving opening at one side thereof, a foot portion adjacent to one side of said receiving opening, a lead portion bent outwardly from said loop at the opposite side of said receiving opening and extending in a direction away therefrom, a retaining finger continuing inwardly from said lead portion in a direction transversely to the loop, and normally disposed adjacent to the foot portion, the said foot portion having a U-shaped slit therein forming a retaining tongue and a slot extending from said slit to receive the shank of a fastening member underneath the head thereof; the said tongue being normally disposed in front of said slot to prevent the passage of the shank from the slot, but being bendable to permit removal of the tongue from in front of the slot to thereby permit the passage of the shank into the slot, and a lead portion on the foot portion bent upwardly from the plane of the foot portion and projecting into the said receiving opening to guide a member over the head of the said fastening member.

WILLIAM N. ALESHIN.
